L. J. WAHL

ELECTRIC CLIPPER

Filed Sept. 22, 1922

FIG. 1

FIG. 3

FIG. 2

FIG. 4

FIG. 5

INVENTOR
Leo J. Wahl,
BY Walter N. Haskell,
his ATTORNEY

UNITED STATES PATENT OFFICE.

LEO J. WAHL, OF STERLING, ILLINOIS.

ELECTRIC CLIPPER.

Application filed September 22, 1922. Serial No. 589,919.

To all whom it may concern:

Be it known that I, LEO J. WAHL, a citizen of the United States, residing at Sterling, in the county of Whiteside and State of Illinois, have invented certain new and useful Improvements in Electric Clippers, of which the following is a specification.

My invention has reference to electric clippers such as are specially designed for use in barber shops, and belongs to that type of instrument wherein the actuating devices are contained within the handle, or casing of the tool. In devices of this class which are now in use if the blades become worn or get out of adjustment, it is a difficult matter to regulate the same, and the removal and replacement of the blades calls for the use of a considerable amount of time.

One of the purposes of the present invention is to provide a novel control mechanism for the movable clipper blade, whereby a very delicate adjustment of such blade can be made with relation to the stationary blade of the tool.

Another purpose of the invention is to support the movable clipper blade in such a manner that the same can be quickly removed from the tool, and sharpened, or replaced by another blade, if desired.

Another object of the invention is to provide means for exerting a desired amount of pressure upon the movable blade, at a point near the operating edge thereof.

Another purpose of the invention is to increase the general efficiency and durability of the tool.

The above-mentioned, and other features and advantages of the invention will be more fully understood from the following specification, reference being had to the accompanying drawings, in which:

Fig. 1 is a vertical longitudinal section of the device.

Fig. 2 is a plan view thereof, with the upper casing plate removed.

Fig. 3 is a detail of the plate 16.

Fig. 4 is a detail of the blade 4, in perspective.

Fig. 5 is a side elevation of the tool, complete.

The invention comprises a hollow handle or casing, formed of parts 1 and 1^a, the part 1^a being attached to the other part so that it can be disconnected therefrom, if desired. When united, the two parts form an

instrument which can be conveniently grasped by the hand of the operator. To one end of the part 1 is secured a stationary clipper blade 2, provided with the usual series of teeth 3, and slidable on the blade 2 is a blade 4, provided at its outer edge with a series of teeth 5, coacting with the teeth 3 when the tool is in operation. In an enlargement 6 of the casing is secured an electro-magnetic coil 7, at one end of which is supported a plate 8, by means of a resilient arm 9, attached at one of its ends to the inner face of the casing 1, by means of a bolt 10. The plate 8, which is of softer metal than the arm 9, is in close proximity to the core 11 of the coil 7, and operates as an armature therefor, so that upon such coil being suitably energized, a rapid vibratory movement is given to said plate. The plate 8 is bent at its free end into an arm 12, to the outer face of which is secured a frame 13, having a pair of parallel plates provided with threaded perforations to receive a similarly threaded screw 14, the end of which engages a small depression 15 in the blade 4. Between the frame 13 and arm 12 is secured a thin plate 16, the lower edge of which acts as a support for a rib 17 on the blade 4, and prevents such blade from twisting or turning upon the pivot formed by the end of the screw 14, while the blade is in operation. The lower edge of the plate 16 also bears against the inner edge of the blade, and holds the same in proper operative position. The frame 13 and plate 16 are held in place by means of a pair of screws 19, passing through openings 20 in the plate 16. These openings are of greater diameter than the screws, permitting of an adjustment of the plate 16 vertically or transversely.

The spacing of the plate 8 with relation to the coil can be regulated by means of an adjustment screw 21 in the wall of the casing 1, and the coil 7 is fitted with wires 22, passing through openings in the small end of the handle, and designed for connection with a suitable source of electrical power. In practice, these wires would be formed into a cord, and fitted with a socket for connection with the usual mercantile system of light or power. If the current of electricity which is supplied is of an alternating or intermittent character, a rapid vibratory movement will be given to the arm 8, thereby imparting to the blade 4 a rapid oscil-

lating action transversely of the tool. This operates the clipper teeth in the usual manner, with the desired results.

By a proper operation of the screw 14, by means of a thumb-turn 18 thereon, the pressure exerted by said screw upon the blade 4 can be gradually increased or diminished, at will. The screw is positioned so that the force thereof will be imparted nearest the cutting edge of the blade, as shown, as a result of which the response of the blade to the action of the screw is quicker, and the application of the force thereof more positive, than if such screw were stationed at a point farther from said cutting edge. The screw is preferably mounted in the frame 13 so that there will be sufficient friction upon the threads of the screw to prevent accidental turning thereof, and in case the threads should become worn, resulting in a loosening of the screw, this can be overcome by bringing the supporting plates of the frame a little closer together. To accomplish this the screw is removed from the frame, the frame detached from the tool, and the plates pounded or otherwise forced a little closer together. They then have the operation of a lock-nut upon the screw.

It will be evident that a very limited amount of rotation of the screw 14 will serve to release the blade 4, which can be slipped from its position as soon as the screw and blade are disengaged. This is a great advantage where the clipper is subjected to considerable use, and a change of blades is frequently desired.

Changes can be made in the form and arrangement of the device, without departing from the spirit of the invention, as herein set forth and claimed.

What I claim and desire to secure by Letters Patent, is:

1. A device of the class described, comprising a hollow handle, provided at one of its ends with a stationary clipper blade; a clipper blade slidable on said first-named blade; an electro-magnetic mechanism contained in said handle and adapted for connection with a suitable source of power; an armature member supported in said handle so as to receive a vibratory action from said electro-magnetic mechanism; and means attached to said armature member, having a loose connection with said movable blade, and capable of exerting a desired amount of pressure thereon.

2. A device of the class described, comprising a hollow handle, provided at one of its ends with a stationary clipper blade; a movable clipper blade adapted to cooperate with said first-named blade; an electro-magnetic mechanism contained in said handle and adapted for connection with

a suitable source of power; an armature member supported in said handle so as to receive a vibratory action from said electro-magnetic mechanism; means for connecting said armature member with said movable blade, capable of exerting a pressure thereon; and means for varying the degree of said pressure, at will.

3. A device of the class described, comprising a hollow handle, provided at one of its ends with a stationary clipper blade; a movable clipper blade cooperable with said first named blade; and provided with a transverse rib; an electro-magnetic mechanism contained within said handle; an armature member supported in said handle so as to receive a vibratory action from said electro-magnetic mechanism; a connecting mechanism between said armature member and movable blade, comprising a frame fixed to said armature member, carrying a set-screw having a pivotal connection with said movable blade; and a plate also connected with said armature member, and having a bearing against said rib, to form a guide for said movable blade during its operation.

4. A device of the class described, comprising a hollow handle, and clipper blade fixed thereto; a movable blade cooperating with said first-named blade; an electro-magnetic mechanism contained in said handle; an armature member supported in proximity to said electro-magnetic mechanism, so as to receive a vibratory action therefrom; a frame connected with said armature member, so as to move therewith; an adjustable member carried by said frame and having a pivotal connection with said movable blade, at a point approximate the operating edge thereof; and means also carried by said armature member, for holding said movable blade in proper position while in action.

5. A device of the class described, comprising a hollow handle, provided with a stationary clipper blade; a movable clipper blade cooperable with said first named blade, and provided with a transverse rib; an electro-magnetic device contained in said handle; an armature member supported in said handle, so as to receive a vibratory action from said electro-magnetic devices; a connecting mechanism between said armature member and movable blade, adapted to exert pressure thereon at a central point; and a plate also connected with said armature member, capable of cooperating with said rib, to hold said movable blade in proper position while in action, said plate being capable of adjustment vertically or transversely of said handle.

In testimony whereof I affix my signature.
LEO. J. WAHL.
